FRANCIS JOSEPH COLLIN, OF DORTMUND, GERMANY, ASSIGNOR TO AKTIEN-GESELLSCHAFT FÜR KOHLENDESTILLATION, OF DUSSELDORF, GERMANY.

COKE-OVEN.

1,157,368.

Specification of Letters Patent. Patented Oct. 19, 1915.

Application filed February 21, 1912. Serial No. 679,068.

To all whom it may concern:

Be it known that I, FRANCIS JOSEPH COLLIN, a subject of the King of Prussia, and residing at Dortmund, Kingdom of Prussia, 5 German Empire, have invented certain new and useful Improvements in Coke-Ovens, of which the following is a specification.

The present invention relates to that type of coke ovens which is generally designated 10 as horizontal ovens and is particularly directed to that part of such structures which controls the supplying of combustion gases to the individual nozzles in the walls between the coke chambers.

15 In the drawings there are illustrated three variations of structure.

Figure 1 is a longitudinal section through one of the heating walls, and Fig. 2 represents a transverse section on the line *a*—*b* of Fig. 20 1. Figs. 3 and 4, and 5 and 6 respectively are similar views of two alternative forms, Fig. 4 being a section on line *c*—*d* of Fig. 3, and Fig. 6 a section on line *e*—*f* of Fig. 5. Fig. 7 is an enlarged detail of a portion of 25 the oven shown diagrammatically in Fig. 1. Fig. 8 is a transverse section on the line *g*—*h* of Fig. 7 and Fig. 9 is a transverse section on the line *i*—*k* of Fig. 7.

According to the present invention the 30 combustion gases are supplied to the nozzle not directly from the source of supply but from a more or less centrally located reservoir or chamber which being enlarged as compared with the transverse sectional dimensions of the gas supply (cf. 1 of Figs. 1, 3 and 5 with 1^a of Figs. 2, 4 and 6) acts 35 as a temporary storage chamber from which each of the nozzles draws its supply. As shown in the drawings the duct which supplies 40 the incoming gases, the storage chamber for these gases and the ducts leading from said chamber to the nozzles are all built into the masonry of the oven in that part thereof which is located beneath the 45 flues. The main object of these constructions is to prevent the gases from becoming overheated. In order to bring about this result the full quantity of the gas is first passed undivided to the center of the oven where 50 due to the enlargement of the chamber the movement of the gas is retarded before they are distributed to the individual nozzles.

In addition to the supplying of the gas in such a way as to prevent its overheating and consequent decomposition, the construction, 55 as will readily be seen, is such that the gas that feeds the nozzles nearer the coolest ends of the oven is subjected to the greatest heat so that the degree of preheating is adjusted throughout the oven to the relative temperature of the oven at any point. The entire 60 gas supply system as shown in the drawings, is located in that part of the walls which is subjected to the least amount of radiated heat *i. e.* below the nozzles and 65 heating flues—an arrangement which, when employed, brings about more satisfactory results than if the gas supply system were incorporated in a hotter part of the structure.

In the drawings the centrally located 70 chamber is designated with numeral 1. In Figs. 1 and 2 the gases are introduced into the wall of the oven through the channel 1^a from which they enter the enlarged chamber 1 which is located near the center of the wall. 75 This arrangement is duplicated at the other side of the wall so that there are two of such chambers 1 near the center of the wall. From the chamber 1 the gases distribute themselves to the individually gaged or calibrated nozzles 2 through which they enter the individual flues 3 in which they meet the air used for combustion which enters through the inclined slits 5 which communicate with the common air supply flue 6. The 80 coking chambers are designated by the numeral 7. The products of combustion pass from the flues 3 into the small flues 7 (see Figs. 7 and 9) and pass downwardly there-through into the sole flues 8 of the adjoining oven (see Figs. 8 and 9). These sole flues 8 alternate with the air supply flues 6 and discharge the incandescent combustion products, if desired, into suitably constructed and arranged regenerators (not 85 shown). During one phase of the operation a particular regenerator is being heated in this manner while during the next phase the heated regenerator is connected with the air supply for preheating the air before its passage through the flues 6 and slits 5 into the combustion flues 3. In Figs. 3 and 4 the combustion gases instead of being withdrawn from the chamber 1 through the com- 90 100

mon flue which communicates with each of the nozzles 2 (as shown in Fig. 1) are supplied to groups of nozzles by separate and independent passages and chambers; but here again the gases are first permitted to accumulate in a common reservoir or chamber 1 before any of the nozzles can be supplied. Figs. 5 and 6 illustrate an oven built just like the one shown in Figs. 1 and 2 except that the two chambers 1-1 of Fig. 1 are merged into a single chamber. In that case the entering flue 1^a through which the gases are conducted to the chamber 1 need be located only on one side of the oven instead of at both as would be the case if the structure of Fig. 1 is employed.

When gases are distributed according to the method thus described, there will always be near the center of the oven a relatively large accumulated supply of gas sufficient to supply in adequate measure the requirements of the various burner nozzles. The heat in the oven has a tendency to cause the separation of a certain amount of hydrocarbons out of the combustion gases, but where a central reservoir or chamber is used, such effects are negligible by reason of the capacity of the chamber 1 to act as a storage chamber for an enlarged or accumulated common source of supply. The clogging up of the heating flues or nozzles by means of such decomposition or separation of heavy hydrocarbons is thus very much diminished if not entirely obviated and the gases being maintained in large volume in the center of the oven are not exposed to the likelihood of becoming overheated.

The essence, therefore, of the present invention resides in the fact that the full quantity of gas is first brought in an undivided condition to about the middle of each wall where it accumulates in a common chamber, preferably enlarged, from which chamber it is first divided and distributed to the individual nozzles. Moreover, a pre-heating of the gas is effected in the flues leading from the central chamber to the nozzles whereby the gas conducted to the nozzles near the oven ends, which are the coolest parts of the oven, travels the longest distance and is therefore most strongly pre-heated while that conducted to the nearer nozzles is less strongly pre-heated. In this way the heat is properly distributed throughout the oven, the degree of pre-heating being adjusted throughout the oven to the relative temperature of the oven at any point.

What I claim is:

1. In a coking oven the combination of an aligned series of combustion flues provided with individual burner nozzles, a chamber located approximately half way of the oven's length, the said chamber being

enlarged in comparison with the transverse sectional area of that passage which supplies gas to said chamber from the outside of the oven, a passage leading from said chamber to a plurality of burner nozzles and a gas supply passage connecting said chamber with the gas supply outside of the oven and so arranged as to supply to the said chamber in undivided volume the total quantity of gas required for all the burner nozzles, the said two sets of passages connecting with each other only by reason of their respective connections with the said chamber.

2. In a coking oven a heating wall provided with a series of heating flues, a chamber located in that part of the wall below the plane of said flues and approximately near the center of said oven wall, a passage for supplying gas to said chamber directly and in undivided volume from the outside of said wall; and a second passage extending from said chamber toward the outer end of the wall and supplying a plurality of burner nozzles with gas drawn from said chamber, the said two passages being also located in that part of the wall below the plane of said flues.

3. In a coking oven a heating wall provided with a series of heating flues, a chamber located approximately near the center of said oven wall, nozzles connecting a plurality of said flues directly with said chamber, a passage for supplying gas to said chamber directly and in undivided volume from the outside of said wall; and a second passage extending from said chamber toward the outer end of the wall and supplying a plurality of burner nozzles connecting each of the remaining flues in said series of flues with said second passage.

4. In a horizontal coking oven the combination of a series of coking chambers spaced apart by heating walls, each heating wall being composed of a series of individual heating flues; means for conducting the entire quantity of gas required to supply a predetermined set of said heating flues in undivided volume from the outside of the oven to a chamber located in the lower part of the oven, a chamber to receive said gas supply located approximately at the center of the wall; means to supply the entire series of individual heating flues from said chamber, said means, chamber and conducting means being located in that part of the oven wall beneath the heating flues, an air supply chamber located beneath the coking chambers and passages leading from said air chamber to each heating flue near the point of combustion.

5. In a coking oven a heating wall provided with a series of heating flues, a chamber located approximately near the center

of said oven wall, a passage for supplying gas to said chamber directly and in undivided volume from the outside of said wall, and a plurality of distributing passages extending from said chamber toward the outer end of the wall, each supplying a predetermined group of nozzles.

In testimony whereof, I have hereunto set my hand in the presence of two subscribing witnesses.

FRANCIS JOSEPH COLLIN. [L. S.]
